UNITED STATES PATENT OFFICE.

AUGUSTUS BEALS, OF NORTH WEYMOUTH, MASSACHUSETTS.

HAMMOCK-HOLDER.

SPECIFICATION forming part of Letters Patent No. 429,409, dated June 3, 1890.

Application filed December 13, 1889. Serial No. 333,644. (No model.)

To all whom it may concern:

Be it known that I, AUGUSTUS BEALS, of North Weymouth, in the county of Norfolk and State of Massachusetts, have invented 5 certain new and useful Improvements in Hammock-Holders, of which the following is a specification.

This invention has for its object to provide a simple and effective hammock holder or 10 ring adapted to hold the ends of the longitudinal strands of the hammock, and of such construction that it may be engaged with or locked to a supporting-rope by the weight of the hammock without positive connection 15 with said rope, so that the rope may be readily disengaged from the hook or moved to increase or decrease its operative length.

To these ends the invention consists in a 20 hammock hook or ring comprising a loop to receive the strands of the hammock, a hook formed on the back of said loop to receive a supporting-rope, and two oppositely curved or bent prongs or holders on one side of the 25 loop, said holders being arranged to hold the free portion of the rope substantially at a right angle to the portion which passes through the hook, so that the hook will have a sufficient frictional hold or grip upon the rope to prevent the latter from slipping 30 through the hook, as I will now proceed to describe.

Of the accompanying drawings, forming a 35 part of this specification, Figure 1 represents a perspective view of my improved hook or loop and a portion of the supporting-rope, Fig. 2 represents a bottom view, and Fig. 3 an edge view of the same.

The same letters of reference indicate the 40 same parts in all of the figures.

In the drawings, *a* represents the loop, 45 which has a form adapting it to hold the end strands of a hammock, said strands being secured to the substantially straight side 2 of the loop. Upon the outer side of the back of 50 the loop is formed a hook *b*, adapted to receive the supporting-rope *c*, the sides of the rope-receiving recess of said hook being substantially at right angles to the bottom side of the hook, the intersection of said sides and 55 bottom forming an angle 3, Fig. 3. The portion of the rope *c* that is held in the recess of the hook is therefore about at a right an-

gle with the plane of the loop, as shown in Fig. 3.

dd' represent two prongs or holders formed 55 on or attached to the under side of the loop, said prongs being curved or bent in opposite directions and constituting hooks, one of which is open at one side and the other at the 60 opposite side, as shown in Fig. 1.

The hooks or holders *d d'* are arranged to receive the free portion or end of the rope *c* and hold the same substantially at a right angle with the portion that is in the recess of the hook *b*. The rope is thus caused to bind 65 on the angle 3 at the lower side of the hook, so that the hook has a sufficient friction hold or grip on the rope to prevent it from slipping, said hold being increased by contact of the angle 4 at the upper end of the recess of 70 the hook with the rope.

The prongs or hooks *d d'*, bearing the one 75 on one side and the other on the opposite side of the rope, prevent the latter from moving laterally in either direction, so that while the free end of the rope can be quickly engaged 80 with and disengaged from the prongs or hooks by any suitable manipulation it cannot become disengaged from either accidentally, nor can it slip accidentally out of the recess 85 of the hook *b*.

I prefer to make the hook *b* somewhat thicker than the body of the loop, as shown in Fig. 3, thus not only increasing its strength, but also increasing the length of its rope-receiving recess and giving it a greater frictional hold on the rope.

It is to be observed that the form of the 90 loop or ring *a* may be varied to adapt the same for attaching clothes-lines thereto, or in order to suit it to other uses in which it may be found available, the invention not being confined to employment in connection with hammock-supports.

I claim—

The improved hammock-holder hereinbefore described, the same consisting of the 95 loop *a*, the hook *b*, formed on the back of the loop and having a rope-receiving recess which is open at one end and has sides which are 100 substantially at right angles with the sides of the loop, and the oppositely curved hooks or holders *d d'* on the under side of the loop arranged to receive the free end of the rope, said

hooks being formed to extend in opposite directions across the free end of the rope, and thereby hold the same substantially at a right angle with the portion of the rope that is within the recess of the hook *b*, as set forth.

5 In testimony whereof I have signed my name to this specification, in the presence of two

subscribing witnesses, this 30th day of November, A. D. 1889.

AUGUSTUS BEALS.

Witnesses:

A. D. HARRISON,
ARTHUR W. CROSSLEY.
